MEANS FOR EXPANDING A RECEIVED
PULSE RADIO SIGNAL

Arthur A. Varela, Washington, D. C.

Application October 27, 1938, Serial No. 237,222

16 Claims. (Cl. 250—8)

(Granted under the act of March 3, 1883, as
amended April 30, 1928; 370 O. G. 757)

1

This invention relates to means for producing an output of relatively high power and long duration in comparison with the power level and duration of a radio pulse signal of extremely short duration.

Among the several objects of this invention are:

To provide radio receiver circuits whereby a very short received signal may be expanded into an output signal persisting for a relatively long time after cessation of the received signal;

To produce an output of considerable power in response to a received signal of low power;

To convert a signal of very high frequency and extremely short duration into a response at audio frequency and of appreciable duration.

In the drawings:

Fig. 1 depicts schematically one form of my invention;

Fig. 2 shows by graphs the relative duration of a received pulse and the response produced thereby, together with certain voltage relations involved;

Fig. 3 shows schematically a further embodiment of the present invention wherein the energy in the system is twice rectified.

The present invention is adaptable to all frequency bands and to wire telegraph communication, but has particular application in high frequency radio communication and control in which it is desired to use very low power in the transmitter and simple transmitting equipment.

My invention has further application in extending the upper frequency limit of communication with superfrequency negative grid transmitters in that oscillation in the transmitter exists during only a very small fraction of the operating time and therefore anode voltages of unusually high value may be employed with consequent reduction of electron transit time within the tubes, thus permitting operation at very high frequencies.

The transmitter utilized in connection with this invention sends a single pulse of very short duration to signal a dot and three evenly-spaced similar pulses to signal a dash. The frequency of the receiver output may be adjusted to give an audio note of any desired frequency by adjusting the frequency of an output oscillator, to be described hereinafter, and the duration of the output signal in response to a three pulse signal is substantially three times as long as the response to a single pulse. Since the duration of the transmitted pulse may be of the order of one microsecond or less the effective gain of this system over conventional means is enormous.

2

This invention has some points of similarity to that set forth in my co-pending application Serial No. 237,221, filed October 27, 1938. The principal advantage of the system herein described over that forming the subject of my said co-pending application lies in the higher power gain. Also, the present system may be used at low radio frequencies, where the system of my said co-pending application would not be desirable.

Transmitters adapted for use with this invention are described in the application of R. M. Page, Serial No. 223,503, filed August 6, 1938, now Patent No. 2,541,092 issued February 13, 1951. The only adjustment of such transmitters necessary to make them usable with this invention is that the pulsing rate of the transmitter be fixed so that one pulse is transmitted for a dot and three for a dash.

20 Briefly stated, the receiver shown in Fig. 1 consists of a self-quenching oscillator in which oscillation is initiated by the received pulse. During oscillation this oscillator produces a reduced bias on a second oscillator operating at audio frequency, thereby causing the second oscillator to cut off after quenching of the first oscillator is delayed by energy accumulated in a condenser, the discharge of which to effect the desired result is produced by a diode valve. A series of 25 recurrent pulses of proper time interval will therefore maintain the audio oscillator in a state of oscillation for a time proportional to the number of pulses received in the series.

The input to Fig. 1 is shown as a dipole 4, although it may be the output of any conventional amplifying means. The input is coupled to tuned grid circuit 5 which is in turn tightly coupled to tuned plate circuit 6, the tuned circuits respectively including the grid 7 and anode 8 of vacuum tube 9. The circuit 5 will obviously be tuned to the frequency of the signal to be received and the circuit 6 will likewise be tuned to that frequency to constitute, with tube 9 and other elements, an oscillatory network. Voltage 35 divider 10 is adjusted to bias grid 7 to a point that is just below the value of grid bias at which oscillations begin. Resistor 11 in series with cathode 12 is of such value as to prevent continuous oscillation after the received signal has 40 ceased and capacitor 62 is connected across resistor 11 and is of such value that it delays the quenching of oscillation for the desired time interval but gradually builds up to such potential that oscillations are extinguished.

Anode 13 of rectifier 14 is connected to the high potential side of resistor 11 to be set into

operation by the potential there developed during oscillation and the cathode 15 of rectifier 14 is connected to control grid 16 of vacuum tube 17. Tuned plate circuit 18 is connected to anode 19 of tube 17 and is coupled with circuit 20 to constitute an oscillatory system, the values of the elements in circuits 18 and 20 being such that their output is within the audio range. The fixed bias on grid 16 is derived from voltage divider 22. Connected in parallel between grid 16 and 10 voltage divider 22 are the capacitor 23 and resistor 24, the value of resistor 24 being much higher than the effective resistance of diode 14 while the latter is passing current, and therefore the time of discharge of capacitor 23 through resistor 24 is considerably longer than the time during which current is passing through the diode 14 to charge capacitor 23. The effective bias on grid 16 does not follow the voltage on capacitor 23 but is held to a fairly constant value by resistor 25 and capacitor 26 in parallel with each other and in series with cathode 27. The anode supply 28 and bypass capacitors 29 and 30 are conventional.

The operation of the system above described may be explained in connection with Fig. 2. A signal pulse impressed upon tuned input circuit 5 is represented by the sharply peaked curve P, the small time period occupied by the pulse being indicated by the shortness of the base. When the pulse voltage reaches the value e at time T_0 tube 9 begins to oscillate and capacitor 23 begins to charge as shown by curve a and audio oscillator tube 17 begins to operate. At the time designated T_1 sufficient bias has been built up on capacitor 62 to extinguish the oscillations in tube 9 and capacitor 23 then begins to discharge with its potential following the curve b and when this potential has dropped to the value represented by the dashed line e_1 , at time T_2 , the tube 17 ceases to oscillate at time T_2 . This is the condition when a single pulse, representing a dot, is received. It is apparent from Fig. 2 that the duration of the received pulse is short compared to time T_0-T_1 , and that this time is short compared to time T_1-T_2 . It is to be understood that these values are not to scale, since the pulse duration may be one microsecond while T_0-T_1 may be 0.005 second.

However, if a dash is being transmitted a second pulse P_2 is received and the operating voltage e on grid 7 is reached before the potential of capacitor 23 has dropped to the value e_1 , and therefore the audio oscillator is maintained in operation through the time of a second discharge of capacitor 23. It is obvious that so often as a new pulse is received before the potential of capacitor 23 drops to value e_1 , the tube 17 will continue in uninterrupted oscillation, and hence the reception of three pulses, representing a dash, would mean merely adding another pulse and discharge curve to Fig. 2. Thus, the audio frequency signal in phones 31 for a dash would have substantially three times the duration for a dot.

The system shown in Fig. 3 provides greater facility of tuning and the first oscillator is not self-quenching, but otherwise the action of the two systems is very similar. Here the tuned input circuit 32 is connected to anodes 33 of a full wave rectifier 34, whereof the cathodes 35 are connected to grid 36 of oscillator tube 37. The oscillatory network of this tube includes tuned circuit 38 connected to anode 39 and a further tuned circuit 40 connected to additional grid 41.

The rectifier 34 is biased against operation below a predetermined signal level through connection 42 to voltage divider 43 and the bias on grid 36 is derived through connection 44 to the voltage divider.

Upon reception of a signal and passage of current through rectifier 34 the capacitor 45 in parallel with resistor 46 between cathodes 35 and grid 36 on the one side and voltage divider on the other, becomes charged and after cessation of current through the rectifier 34 the energy stored in capacitor 45 discharges through resistor 46 and maintains the tube 37 in oscillatory condition for a time longer than the duration of current passage through rectifier 34. Capacitor 47 and resistor 48 in parallel between cathode 49 and ground maintain a steady bias that does not follow the voltage at capacitance 45. Upon the discharge of capacitor 45 to a potential less than that required to maintain tube 37 in an oscillatory condition, the oscillations cease.

Rectifier 50 has its anode 51 connected to the high potential side of resistor 48 and its cathode 52 connected to grid 53 of audio oscillator tube 54. Voltage divider 55 provides the bias for extinguishing oscillation when the potential built up on capacitor 56 across resistor 57 by current through rectifier 50 has dropped below a predetermined value. Again, the value of resistor 57 is large in comparison with the effective resistance of rectifier 50 while passing current, and therefore the discharge of capacitor 56 through resistor 57 is longer than the time of charging capacitor 56, and hence the duration of oscillations in audio oscillator tube 54 is longer than the duration of oscillations in tube 37. The oscillatory network of tube 54 includes tuned circuit 58 connected to anode 59 and tuned circuit 60 connected to additional grid 61. The audio output is perceptible by use of phones 31. It is thus apparent that the very high frequency pulse of extremely short duration is twice expanded in length and a response of audio frequency and of perceptible duration is derived, and that the time of the audio response may be varied to indicate either a dot or a dash.

The invention herein described and claimed may be used and/or manufactured by or for the Government of the United States of America for governmental purposes without the payment of any royalties thereon or therefor.

I claim:

1. A method of radio communication, comprising the steps of receiving a signal pulse, applying said pulse to initiate electric oscillations with transfer of energy while said oscillations persist, utilizing a portion of the said transferred energy to build up gradually a potential that extinguishes said oscillations after a predetermined time, rectifying another portion of said energy, and utilizing said rectified energy to initiate and maintain other electric oscillations for a time longer than said predetermined time of duration of the first oscillations.

2. A method of radio communication, comprising the steps of receiving a train of signal pulses wherein the time between two succeeding pulses is long compared with the duration of one pulse, applying each said pulse to initiate electric oscillations with transfer of energy while said oscillations persist, utilizing a portion of the said transferred energy to build up a potential that extinguishes said oscillations after a substantial portion of the time between two succeeding pulses, rectifying another portion of said energy, and

utilizing said rectified energy to initiate and maintain other electric oscillations for a time longer than the duration of said first oscillations.

3. A method of radio communication, comprising the steps of receiving a train of signal pulses wherein the time between two succeeding pulses is long compared with the duration of one pulse, rectifying the full waves in each said pulse, applying the rectified energy to initiate first electric oscillations and to store energy to maintain said oscillations for a time long in comparison with the duration of a pulse with transfer of energy while said oscillations persist, applying and storing the said transferred energy to initiate second electric oscillations and to maintain said second oscillations for a time longer than the duration of said first oscillations.

4. A method of radio communication, comprising the steps of receiving a train of signal pulses wherein the time between two succeeding pulses is long compared with the duration of one pulse, rectifying at least a portion of the energy in each said pulse, applying the rectified energy to initiate first electric oscillations and to store energy to maintain said oscillations for a time long in comparison with the duration of a pulse with transfer of energy while said oscillations persist, applying and storing the said transferred energy to initiate second electric oscillations and to maintain said second oscillations for a time longer than the duration of said first oscillations.

5. Radio receiving apparatus, comprising a vacuum tube having a cathode, a grid and a plate, a tuned grid-tuned plate oscillatory network connected to said tube, input means feeding into the tuned grid part of said network, means to bias said tube to prevent oscillations in the absence of signal in said input, a first capacitance and a first resistance in parallel between said cathode and said biasing means, a second vacuum tube having a plurality of electrodes including a cathode, a grid and a plate, second oscillatory network connected to electrode elements of said second tube, means to bias said second tube to prevent oscillations in the absence of signal upon said grid thereof, a second capacitance and a second resistance in parallel between said biasing means for the second tube and the grid thereof, a rectifier having an anode connected to the high potential side of said first resistance and a cathode connected to the grid of said second tube and to said second capacitance and second resistance, the resistance of said rectifier being less than that of said second resistance and audio output means connected to the plate of said second tube.

6. Radio receiving apparatus, comprising a vacuum tube having a cathode, a grid and plate, a tuned grid-tuned plate oscillatory network connected to said tube, input means feeding into the tuned grid part of said network, means to bias said tube to prevent oscillations in the absence of signal in said input, means connected to be fed by the plate-cathode current of said tube to build up a potential to extinguish oscillations in said network, a rectifier having an anode connected to the high potential side of said means and a cathode, a second vacuum tube having a plurality of electrodes including a grid connected to the cathode of said rectifier and a cathode, a second oscillatory network including two electrodes of said second tube, a capacitance and a resistance each having one side connected to the cathode of said rectifier and to the grid of said second tube and the other side operative-

ly connected to the cathode of said second tube, the value of said resistance being greater than the resistance of said rectifier, and means to bias said second tube to extinguish oscillations when the potential on the grid of said second tube becomes less than a predetermined value.

7. Radio receiving apparatus, comprising a vacuum tube having a cathode, a grid and plate, a tuned grid-tuned plate oscillatory network connected to said tube, input means feeding into the tuned grid part of said network, means to bias said tube to prevent oscillations in the absence of signal in said input, means connected to be fed by the plate-cathode current of said tube to build up a potential to extinguish oscillations in said network, a rectifier connected to be biased for operation by said potential, a second vacuum tube having a plurality of electrodes, a second oscillatory network including two of the said electrodes of the second tube, a second means fed by the current through said rectifier to build up on said second means a potential, said second means including an element having an impedance higher than the resistance of said rectifier, means connecting said second means to said second tube to initiate and maintain oscillations in said second network while the potential on said second means is greater than a predetermined value, and means to extinguish oscillations in said second network when the potential on said second means drops below said predetermined value.

8. Radio receiving apparatus, comprising oscillator means to pass current when oscillating, input means to transfer signal energy to initiate oscillations in said oscillator means, means to prevent oscillation of said oscillator means in the absence of signal energy in said input means, means fed by current passed by said oscillator means to build up a potential to block the oscillator after a predetermined time, a rectifier connected to be biased for operation by the potential on the last mentioned means, a second oscillator means, means fed by current through said rectifier to build up a second potential connected to said second oscillator means to initiate and maintain oscillations in said second oscillator means while said second potential is greater than a predetermined value, and means to prevent oscillation in said second oscillator means when said second potential is less than said predetermined value.

9. Radio receiving apparatus, a full wave rectifier having two anodes and two cathodes, a tuned input to said anodes, means to bias said anodes to prevent operation below a predetermined signal level, a capacitance and a resistance in parallel connected in the cathode-anode circuit, the value of said resistance being greater than the resistance of said rectifier while passing current, a vacuum tube having a plurality of electrodes including a cathode, a grid and an anode, means connecting said grid to the high potential side of said capacitance and resistance and to said biasing means, an oscillatory network including two of said electrodes, a second capacitance and second resistance in parallel with each other and in series with the cathode of said tube, a second vacuum tube having a plurality of electrodes including a cathode, a grid and an anode, a second rectifier operatively connected to the high potential side of said second resistance and to the grid of said second tube, means to bias said second tube, a third resistance and a third capacitance in parallel connected at one side to said

grid and the output of said second rectifier and at the other side to said biasing means for said second tube, the value of said third resistance being greater than the resistance of said second rectifier while passing current, a second oscillatory network including two electrodes of said second tube, and audio output means connected to the anode of said second tube.

10. Radio receiving means, comprising a rectifier having input and output means, a tuned circuit connected to said input, means to bias said rectifier to prevent operation thereof below a predetermined input level, a first resistance and a first capacitance in parallel connected in circuit with said input means and said output means, the value of said resistance being greater than the resistance of said rectifier while passing current, a vacuum tube having a plurality of electrodes including a cathode, a grid and an anode, means connecting said grid to the high potential side of said capacitance and resistance and to said biasing means, an oscillatory network including two of said electrodes, a second capacitance and second resistance in parallel with each other and in series with the cathode of said tube, a second vacuum tube having a plurality of electrodes including a cathode, a grid and an anode, a second rectifier operatively connected to the high potential side of said second resistance and to the grid of said second tube, means to bias said second tube, a third resistance and a third capacitance in parallel connected at one side to said grid and the output of said second rectifier and at the other side to said biasing means for said second tube, the value of said third resistance being greater than the resistance of said second rectifier while passing current, a second oscillatory network including two electrodes of said second tube, and audio output means connected to the anode of said second tube.

11. Radio receiving apparatus, comprising a rectifier having input and output elements, an input circuit responsive to a short signal pulse connected thereto, means to bias said rectifier to prevent operation below a predetermined signal level, oscillatory means adapted to pass current when oscillating, means fed by current through said rectifier to build up a potential connected to initiate and maintain for an oscillatory condition in said oscillatory means for a time longer than a signal pulse, a unidirectional current valve connected to be set into operation by current through said oscillatory means, a second oscillatory means, means fed by current through said valve and connected to said second oscillatory means to initiate and maintain an oscillatory condition in said second oscillatory means for a time longer than the duration of said first mentioned oscillatory condition, and output means fed by said second oscillatory means.

12. Radio receiving apparatus, comprising a rectifier, an input circuit and an output circuit connected thereto, said output circuit including energy storage means having a predetermined time constant, oscillatory means connected to said energy storage means to utilize the stored energy to initiate and maintain an oscillatory condition for a time longer than the time of passage of current through said rectifier in response

5 to a signal applied to said rectifier, a unidirectional current valve connected to be set in operation by energy from said oscillatory means during oscillation, a second energy storage means supplied by energy from said valve, a second oscillatory means connected to said second energy storage means to utilize energy stored therein to initiate and maintain a second oscillatory condition for a time longer than the first said oscillatory condition, and output means fed by said second oscillatory means.

13. Pulse receiving apparatus comprising a first normally quiescent self-blocking oscillator, pulse-responsive input means operative to activate said oscillator, a second normally quiescent self-blocking oscillator, and input means for the second oscillator responsive to operation of the first oscillator to activate the second oscillator, said oscillations being self-blocking after predetermined time periods.

14. Pulse receiving apparatus comprising a first normally quiescent self-blocking oscillator, pulse-responsive input means operative to activate said oscillator, a second normally quiescent self-blocking audio oscillator, and input means for the second oscillator responsive to the operation of the first oscillator to activate the second oscillator, said oscillations being self-blocking after predetermined time periods.

15. A pulse repeater system comprising a blocking oscillator, a circuit for receiving pulses from a remotely located pulsing station and for impressing the same on said blocking oscillator for synchronizing the same, and a pulse transmitter under control of said blocking oscillator.

16. A pulse repeater system comprising a blocking oscillator, a circuit for receiving pulses from a remotely located pulsing station and for impressing the same on said blocking oscillator for synchronizing the same, a pulse transmitter under control of said blocking oscillator, and a signal modulation circuit for modulating the pulses produced by said transmitter.
